UNITED STATES PATENT OFFICE.

JACOB B. OTTENHEIMER, OF BALTIMORE, MARYLAND, ASSIGNOR TO OTTENHEIMER BROS. INC., OF BALTIMORE, MARYLAND, A CORPORATION OF MARYLAND.

REFRIGERATOR.

Application filed November 3, 1924. Serial No. 747,596.

This invention relates to refrigerators and particularly to large ice boxes used chiefly by butchers.

In such refrigerators the rack or frame which holds the ice is generally known as the ice bunker, and in order to secure the best circulation and also to economize space this bunker is customarily mounted in the top of the refrigerator; that is, directly above the refrigerated chamber. There must be a free circulation of air from the refrigerated chamber to the top of the ice bunker and thence downward through the bunker back to the refrigerated chamber.

There must also be means to collect and drain away the water resulting from the melting of the ice and the drains for this water must be simple in form and accessible, as they must be frequently wiped out.

In the better types of construction the use of gutters is avoided as far as possible, and this means that the water must be allowed to drip from certain of the higher portions of the structure downward until it has finally collected in the bottom drains of the bunker. This dripping water has a tendency to splash through the air passages, and the purpose of the present invention is to provide a baffle structure which is readily applicable to existing types of refrigerators, which will arrest all splash, and which will not interfere seriously with the air circulation.

Generally stated, the invention contemplates the use of baffles formed of woven wire screen material mounted in the air passages. I prefer that these screens be readily removable and that they may be so located that they drain directly into the gutters.

The preferred embodiment of the invention as applied to a known type of butchers' ice box is illustrated in the accompanying drawing in which:

Fig. 1 is a vertical sectional view through the upper portion of the refrigerated chamber showing the ice bunker;

Fig. 2 is a fragmentary section on the line 2-2 of Fig. 1, and

Fig. 3 is an enlarged fragmentary view showing a portion of the structure as illustrated in Fig. 1.

The walls of the refrigerated chamber are illustrated at 6 and extending from wall to wall are sills 7 on which the ice bunker is supported. The bunker is formed with two

inwardly inclined bottom portions 8 whose construction is not material to the invention except that they are spaced at their opposed edges to form an air port or slot 9 and except that each is provided with a drain gutter 10 at or near its lower edge. The bottom members 8 and the gutters 10 are sheathed with sheet metal 11 so as to render them watertight. The gutters 10 are so located that a man standing in the refrigerated chamber below the ice bunker can reach up through the air port 9 into the gutters 10 so that the gutters are readily accessible for cleaning.

Mounted on the sills 7 is a longitudinal ridge piece 12 which is centered over the opening 9 and which carries a roof or umbrella structure 13 whose edges overlie the two bottom portions 8 of the bunker and hence assure that any water flowing from the umbrella portion will be discharged upon the bottom members 8 and flow thence into the gutters 10. In order to render the umbrella section 13 water-proof and in order also to provide a well-defined drip strip, the umbrella section 13 is sheathed with sheet metal on its upper face, and this metal extends at its edges beyond the umbrella section where it is bent so as to project downward and outward, forming a drip strip 14.

Mounted on the bottom members 8 are two side wall members 15 which are spaced from the wall 6 to afford passages 16 for the upward flow of the circulating air. Supported partly on the filler pieces 17 and partly on the umbrella structure 13 is a grating 18 upon which the ice rests. The ice is confined laterally by slatted frames 19 carried by the walls 15 and by similar slatted frames 20 mounted in a vertical position at the ends of the ice bunker.

An ice bunker constructed as just described offers highly desirable air circulation, and since it is devoid of all gutters except the two gutters 10 which are easily accessible, is easily kept clean and sanitary. The drip from the drip strip 14, however, occasionally causes a splash which passes through the opening 9 into the refrigerated chamber below. It is not desirable to provide gutters in lieu of the drip strip 14, for they would be difficult to clean.

The enlargement of the umbrella section 13 is not desirable for the reason that it tends to obstruct the circulation. The present in-

vention solves the difficulty by suspending from the umbrella section 13 woven wire screens which may conveniently be composed of twelve mesh to sixteen mesh bronze wire 5 mounted in metal frames, though wire of other meshes and different mountings therefore obviously are suitable for the purpose. These frames 21 are mounted on hooks 22 attached to the lower side of the umbrella section 13 in such position that the frames 21 hang below the upper margins of the gutters 10.

This idea of mounting the screen directly above the gutter permits the screen to be 15 loosely mounted so that it is readily removable and so that precision in its manufacture is not essential. Furthermore, water dripping from the screen is immediately collected by the gutter and drained away, a point which is of substantial importance 20 since it is desirable to keep the ice box as dry as possible.

The construction is simple and inexpensive, and is very effective for its purpose. 25 It permits the elimination of all gutters except the two at the extreme margins of the drain pan or bottom section, and yet prevents any splash occasioned by drip from the umbrella section.

30 What is claimed is:

1. The combination of a chamber to be refrigerated; an ice support mounted in the upper portion thereof; an inclined draining bottom beneath a portion of said support, 35 said bottom having a water collecting gutter adjacent its lower edge and there being an air port for directing air past the lower edge of said draining bottom; a water shedding baffle overlying said port and overhanging a portion of said bottom to shield said air port from the direct passage of water; and a splash arresting screen mounted beneath said water shedding baffle in the path of air flowing to said air port, the lower margin of said 45 screen projecting into said gutter below the upper margin of, and out of contact with the walls of, the gutter.
2. The combination of a chamber to be

refrigerated; an ice support mounted in the upper portion thereof; an inclined draining bottom beneath a portion of said support, 50 said bottom having a water collecting gutter adjacent its lower edge and there being an air port for directing air past the lower edge of said draining bottom; a water shedding baffle overlying said port and overhanging a portion of said bottom to shield said air port from the direct passage of water; and a 55 foraminous screen releasably suspended from the lower side of said baffle with its lower margin projecting into said gutter, said screen extending across substantially the entire interval between said baffle and bottom.

3. The combination of a chamber to be 60 refrigerated; an ice support mounted in the upper portion thereof; two reversely inclined drain members below said support spaced apart to form an intervening air port and having gutters near the edges which 65 define said air port; an umbrella structure overlying said air port and arranged to discharge water to said drain members; and splash screens of fine mesh material 70 removably mounted in substantially vertical positions beneath said umbrella structure and extending from the latter substantially to a corresponding drain member, but out of contact with said drain members.

4. The combination of a chamber to be 75 refrigerated; an ice support mounted in the upper portion thereof; two reversely inclined drain members below said support spaced apart to form an intervening air port and having gutters near the edges which 80 define said air port; an umbrella structure overlying said air port and arranged to discharge water to said drain members; and splash screens of fine mesh material 85 removably suspended beneath said umbrella structure and extending downward from the latter into said gutters, but out of contact with said drain members.

In testimony whereof I have signed my name to this specification.

JACOB B. OTTENHEIMER.
